In Switzerland April 16, 1942

9 Claims. (Cl. 51—95)

1

The present invention relates to thread grinding machines in which multigrooved grinding disks are used grinding simultaneously a plurality of convolutions of the thread. The invention relates more particularly to thread grinding machines of the said type in which an infeed movement of a multi-grooved disc is effected automatically during the rotary movement at the operative stroke of the work piece, the work piece and the slide on which the grinding disc is journaled being returned automatically to their initial positions. Each time between said return movements of the work piece and the tool carriage with the grinding disc and the new operating sequence there is effected an additional feed of the grinding disc. The work piece performs little more than one complete revolution during each operative stroke of the work, the grinding disc operates upon all the convolutions. This manner of grinding which is for instance used for grinding screw threads in shouldered work is known as plunge grinding.

Methods are known to grind threads in cylindrical work pieces by means of a grinding disc having a series of peripheral, annular thread-form serrations the length of which disc is less than the length of that portion of the work piece in which threads are to be formed. The work piece is passed axially relatively to the grinding disc the leading end of which is tapering. This method may be called the straight grinding method. If threads are cut by successive operations or strokes, the radial displacement of the grinding disc towards the work piece is adjusted either by hand or automatically. To attain the highest possible efficiency the work to be done by the grinding disc has to be distributed uniformly over the different strokes of the work. Therefore if threads are to be cut in several strokes the infeed has to be reduced for each successive stroke so as to grind away successive increments of the convolutions having the same cross-sectional area.

An object of the invention is to provide an efficient machine to perform automatically the said operations by means of a multi-grooved grinding disc the latter being subjected to equal work at each operation or very nearly so.

The machine according to the present invention may be used for grinding taps, ordinary threads, thread cutting hobs and the like, and may be used also for grinding threads on bolts and for producing and finishing screw threads on shouldered work.

The machine may be adapted for instance to perform the following work:

(1) To produce tools as for instance taps having flutes running transversely to the threads, relieving the teeth of the tap to get a tap of good cutting quality. The relieving is done while the

2

grinding of the threads is being performed. The grinding disc is advanced towards the work while it passes a flute in the tap.

(2) In grinding screw threads it is not advisable to position the grinding disc in its final radial position with reference to the work piece while the latter is at rest and then to grind the convolutions of the threads in but one revolution of the work piece. In doing so the work piece will not be ground truly cylindrical. In the machine according to the invention the grinding disc is fed to its exact radial working position with reference to the work while the latter is rotating. The grinding of all the convolutions is finished in little more than one full revolution of the work.

(3) With the new machine moreover threads in non-fluted work pieces may be quickly and economically ground with extreme accuracy especially in shouldered work pieces. It is of great importance that in such work the convolutions nearest the shoulder should be of exact profile and diameter and moreover as near as possible to the adjacent flank of the shoulder. Care has to be taken that the feed of the grinding disc is performed at the proper rate with reference to the speed at which the work is rotated. The rate of feeding the grinding disc depends largely on the kind and properties of the material of the work piece. The machine according to this invention allows the feeding at the proper rate found by experience without any aid of an operator and without having to take recourse to his carefulness. By carefully advancing the grinding disc to the depth of the cut, the contours of the grinding disc, the wear of the working faces is greatly minimized and the disc needs less truing.

40 The invention consists broadly in a machine for grinding threads comprising means for rotatably supporting the work piece a grinding disc having a plurality of annular grinding serrations or cutting ribs so arranged thereon as to simultaneously work a plurality of threads convolutions of the work piece, means for rotatably supporting said grinding disc, means for producing relative axial movement between the work piece and the grinding disc, and means for automatically producing relative radial movement of work piece and grinding disc so as to grind successive increments in the convolutions of said work piece or to grind the threads at full depth and at about one revolution of the work piece.

45 Other objects and advantageous details and combinations of parts will appear from the description of the invention shown in the accompanying drawings which illustrate by way of example one embodiment of the new grinding machine and also a modification thereof.

In the drawings:

Fig. 1 is a side elevation of the new machine with certain wall portions broken away.

Fig. 2 is a sectional view on the line 2—2 of Fig. 3 and illustrates the feeding mechanism for the slide of the grinding disc.

Fig. 3 is a side view of the grinding machine and also illustrates in part a section on the line 3—3 of Fig. 1.

Fig. 4 is a cross sectional view of the feeding mechanism on the line 4—4 of Fig. 2 in an enlarged scale.

Fig. 5 is a cross sectional view of the driving elements for the feed mechanism on the line 5—5 of Fig. 2 in an enlarged scale.

Fig. 6 is a sectional view on the line 6—6 of Fig. 5.

Fig. 7 is a sectional view of the feeding mechanism for the rolling-in device on the line 7—7 of Fig. 33.

Fig. 8 is a sectional view on the line 8—8 of Fig. 1.

Fig. 9 is a sectional view on the line 9—9 of Fig. 1.

Fig. 10 is a sectional view of the line 10—10 of Fig. 9.

Fig. 11 is a sectional view of the line 11—11 of Fig. 9.

Figs. 12, 13 and 14 are sectional views of the damping valve arranged on the slide of the grinding disc substantially on the line 12—12 of Fig. 2, wherein Fig. 12 illustrates the position of the valve when the slide is in its rearward end position, while Fig. 13 illustrates the position of the valve during the movement of the slide into its working position and in the instant the damping device becomes active, and Fig. 14 illustrates the position of the valve during the grinding operation.

Figs. 15 and 16 illustrate details of the pressure fluid distributor valve in an enlarged scale and in different operative positions. Fig. 15 shows the position of this valve at the beginning of the grinding cycle and Fig. 16 shows the position of the valve at the end of the grinding cycle.

Fig. 17 is a front view of a feeler which cooperates with the feed cams to control the infeed of the grinding disc.

Fig. 18 illustrates a group of three cams as it is used during the grinding operation and also indicates the position of the feeler at the beginning of the grinding cycle.

Fig. 19 illustrates a cam of the feed mechanism which controls the infeed of the tool, particularly during relief grinding.

Fig. 20 is a cross-sectional view of the distributor valve on the line 20—20 of Fig. 8.

Figs. 21 and 22 illustrate diagrammatically the grinding process. Fig. 21 illustrates the grinding operation during the infeed of the grinding disc while Fig. 22 illustrates the infeed of the grinding tool when at the same time a relief grinding operation is to be performed, as in grinding the flutes of a tap.

The Figs. 23, 24, 25 and 26 disclose sectional views of a modified feed mechanism, with a simplified control which views correspond to the Figs. 2, 3, 5 and 6 respectively.

Fig. 27 illustrates diagrammatically the control and feed during the grinding of a right-hand thread with non-interrupted thread convolutions and automatic infeed of the grinding disc.

Fig. 28 illustrates diagrammatically the control and feed during the return movement when

grinding a right-hand thread having non-interrupted thread convolutions and operating with an automatic infeed of the grinding disc.

Fig. 29 illustrates diagrammatically the control and feed during the grinding of left-hand thread with manually controlled infeed of the grinding disc during the production of non-interrupted thread convolutions on the work piece.

Fig. 30 illustrates diagrammatically the control and feed during the truing of a grinding disc in which the control of the machine is adjusted for grinding a right-hand thread with relief grinding on a work piece provided with flutes or interrupted thread convolutions.

Fig. 31 illustrates diagrammatically the control and feed when grinding a left-handed thread having non-interrupted thread convolutions, whereby the infeed of the grinding disc takes place automatically.

Fig. 32 is a top view of the device for rolling in the profiled grooves in the periphery of the grinding disc parts being shown in section on the line 15—15 of Fig. 33.

Fig. 33 is a side elevation of the rolling in device and of the means to control the roller with reference to the grinding disc substantially on the line 13—13 of Fig. 32.

Fig. 34 is a side elevation of the grinding disc and the roller co-operating therewith for profiling the ribs thereof in the line 14—14 of Fig. 32.

Referring to the drawings 1 is a base upon which is slidably mounted a table 2 on which the work is supported and a tool slide 3 on which the grinding disc S is rotatably mounted on shaft 6. The latter is driven by a motor not shown in the drawing. On the table 2 a head stock 4 is fixedly mounted moreover a tail stock 5 which is adjustably arranged on the table 2. A work spindle 11 which is journaled in the head stock 4, is driven by a motor not shown in the drawing. Said motor drives by a worm 192 and a worm wheel 193 an intermediate shaft 191 (Fig. 1). On a key of shaft 191 a clutch member 19 is slidably mounted. The clutch member 19 may be brought in engagement with either of two spur wheels 20, 21 loosely mounted on shaft 191. The spur wheel 20 transmits its rotation by two gears 200 and 201 to a shaft 9 while the spur wheel 21 drives said shaft 9 by a spur wheel 210. By a set of bevel gears 194 a vertical shaft 195 and a worm wheel drive 10 the shaft 9 drives the work spindle 11 in the one or other direction according to the position of clutch member 19. The table 2 is reciprocated by a lead screw 13. The latter is driven by the shaft 9 by means of a train of change-speed gears 12 which drive a counter shaft 196 with two gears 470, 472. With the gear 470 a gear 471 is in engagement and with the gears 471 and 472 two toothed rims 474, 473 of a sleeve 47 may be brought in engagement. The sleeve 47 is slidably mounted on a key of the lead screw 13 and as it may be brought in engagement with either of the gears 470, 471, the direction of the rotation of the lead screw and therefore of the travel of table 2 may be reversed. The sleeve 47 is controlled by a hydraulic piston 46 engaging the sleeve 47 by a fork 475. The piston 46 is controlled by a valve mechanism 18. Both the clutch member 19 and the sleeve 47 may be brought in a neutral position. The valve mechanism 18 comprises a piston 22 which actuates by piston rod 222 and a link 223 a double armed lever 224 the forked lower end of which embraces the sleeve 47. The movements of the piston 22 is controlled by a main controlling valve 23 (Figs.

9 and 10). The latter is rotatably and axially displaceably arranged in a cylinder 36 of the valve body 18. The cylinder 36 is connected by a conduit 48 to a pump P (Fig. 27). A pressure gauge 49 and an automatic relief valve 50 is arranged in said conduit 48. To turn the valve 23 a cap 381 is rotatably mounted in the valve body and on a stud thereof a handle 38 is fastened. A pin 382 of said cap engages a slot 232 allowing the valve piston 23 to slide in axial direction. The handle 38 may be set in any position A, B, C, D indicated in Fig. 1. With the handle 38 in the position A (Figs. 1, 29), the mechanism is set to grind left hand threads the table 2 performing a comparatively long course. If handle 38 is placed into position B (Figs. 1, 27) right hand threads are ground the table 2 performing again a long course. When placed in the position C or D the table 2 travels but a very small way as usual in the plunge grinding operation, in the one position C (Figs. 1, 31) left hand threads are ground and in the position D (Figs. 1, 30) right hand threads are formed.

To control the travel of table 2 the valve 23 and therewith the piston 22 and coupling sleeve 19 have to be operated. To effect this, a pilot piston 233 is arranged in the valve body 18 (Figs. 8, 10). In a notch 231 of piston 233 projects the one arm 271 of a double armed lever 27 rotatably mounted in the base 1. The lever 27 is fastened to a shaft 26 on the upper end of which a two armed handle 25 (Figs. 1, 8) is fastened. One arm 251 projects in the path of two dogs 24 adjustably mounted on the table 2. If a dog 24 strikes against the arm 251 the shaft 26 is turned and displaces pilot piston 233 by the arm 271. The pilot piston 233 initiates the movement of piston 22 by the main valve 23 and piston 22 shifts the sleeve 19 to connect either of the gears 20, 21 with the driving shaft 9. The reversal of the direction of rotation of shaft 9 occasions a reversal in the direction of rotation of shaft 11 and lead screw 13 and of the travel of table 2.

In plunge grinding the table 2 has to travel but a very short way and the work spindle 11 performs but very few rotations. The reversing of the table 2 and spindle 11 by the dogs 24 would not be feasible. For plunge grinding work the pilot piston 233 is operated positively from the shaft 9. On the shaft 9 (Fig. 1) a toothed gear 300 is fastened which driving by means of gear 301, an universal joint 302, a shaft 30 and an universal joint 303 a worm 31 (Figs. 1, 8, 9). The worm 31 meshes with a worm wheel 32 loosely mounted on a shaft 33 (Fig. 8) rotatably mounted in the base 1. The hub of the worm wheel 32 forms a piston sliding in a bore 322 of valve body 18 (Fig. 9) to which oil under pressure can pass by a channel 41 controlled by valve 23. The worm wheel 32 is provided on its outer face with teeth which by axial displacement of worm wheel 32 may be brought in engagement with a clutch member 37 rigidly fixed to shaft 33. The worm wheel 32 is kept out of engagement by a spring 45 arranged in a bore 330 of the shaft 33. One end of the spring is attached to a pin 331 near the end of the bore and the other end to a pin 332 crossing the bore 45 and passing through slots 33 the ends being attached to a ring 321 slidably on the shaft 33 and arranged in a recess of worm wheel 32. By passing oil under pressure from channel 41 into the bore 322 the worm wheel 32 is displaced in axial direction on the shaft 33 against the action of spring 45. When worm wheel 32 is in mesh with the clutch member 37 the rotations of worm wheel 32 and therewith

of shaft 9 are transmitted to shaft 33. On the latter a cam disk 28 (Figs. 8, 20) is fixed and adjacent thereto a cam disk 29 fastened on a sleeve 42 rotatably mounted in the base 1. The opposite faces 281, 291 are apart by an angle α . In this gap projects one arm 272 of lever 27. By turning shaft 33 the faces 281, 291 strike alternatively against arm 272 turning the lever 27 which by its arm 271 shifts the pilot piston 233. The cam discs 28 and 29, which are independent of the dogs 24, are adjustable relatively to each other. For the purpose of changing the angle α the sleeve 42 on which the cam disc 29 is fixed, is rotated relative to the shaft 33. The sleeve 42 is provided with a conical recess 421 into which projects a cone 432 connected to shaft 33 by a key 431. By a nut 44 the cone 432 may be pressed into the recess 421 and then sleeve 42 and disk 29 take part on the rotation of shaft 33. Loosening of the nut 44 permits a rotative adjustment of the sleeve 42 relative to the shaft 33. The work spindle 11 and the shaft 33 are both driven by shaft 9 at a certain predetermined ratio. The sleeve 42 is provided with markings and the cone 43 with an index. The division lines are numbered, the number opposite of the index gives the size of angle α and therewith the number of turns which the work spindle 11 has to perform until a reversing takes place.

The cylinder of the pilot valve 233 communicates with the cylinder of the main controlling valve 23 by conduits 234, 235 and 236 (Figs. 27 to 31). Oil under pressure passes from cylinder 237 of the valve 23 to pilot valve 233 by the conduit 234. In the position of the piston of pilot valve 233 at the left end of its stroke (Figs. 24, 27 to 31) oil passes through conduit 235 into the cylinder 237 and shifts the piston 23 on to the face 3811 (Fig. 9) of the cap 381. The oil passes on through conduit 35 into cylinder 36 and pushes the piston 22 to the right (Figs. 10, 11). The piston 22 shifts the sleeve 19 to the left (Fig. 1), by means of piston rod 222, link 223 and lever 224. The table 2 and the work spindle 11 perform now their working stroke. To initiate the return stroke of table 2 and spindle 11 the lever 27 has to be re-set to shift the piston of the pilot valve 233 to the right (Figs. 10, 27 to 31). In this position oil under pressure passes through conduit 236 into the cylinder 238 of the main valve 23 while the cylinder 237 is emptied, the oil flowing off by the conduits 235, 239. The piston of valve 23 moves until it comes to rest on the face 181. Oil under pressure passes now through conduit 34 into the cylinder 341 and shifts the piston 22 to the left (Fig. 10), oil flows off from cylinder 36 through conduit 35 and channels in the valve 23 into the flow-off pipe 2311. The piston 22 moving to the left (Fig. 10) moves the sleeve 19 again in engagement with the wheel 20. The table 2 returns to its initial position and the spindle 11 turns backwardly. A new cycle of operation may now start as described.

If right hand threads are to be ground the table 2 is moved from the left to the right (Fig. 1) during the working stroke and in opposite direction when left hand threads are to be ground. In grinding left hand threads the piston of the pilot valve 233 has to initiate a working stroke when it is moved to the right (Fig. 10). In this case the piston of valve 23 is moved until it comes to rest on the face 181 (Fig. 27). The hand lever 38 is in its position A. In the conduit 35 is now oil under pressure, the piston 22 is moved to the right (Fig. 10) and the sleeve 19 to the left (Fig. 1) engaging thereby the wheel 21.

By grinding right hand threads and left hand threads, the table 2 is moving in opposite directions during the working stroke. The direction of rotation of the lead screw 13 has to be changed. To effect this change a valve 461 is provided. In the body of the valve 461 the piston 46 is arranged. The spaces 462 and 463 to the left and to the right of piston 46 communicate by conduits 464 and 465 with the main valve 23 (Figs. 27 to 31). If right hand threads are to be ground and with the handle 38 either in the position B or D oil under pressure passes through conduit 465 into the space 463 and shifts the piston 46 and therewith the fork 475 to the right (Figs. 1, 28, 29). Oil flows off from space 462 and passes through conduit 464 and channel 466 to the main valve 23. By the fork 475 the wheels 47 have been moved to the right (Fig. 29). The wheel 473 meshes with the wheel 472 and during the working stroke the table 2 is moved by the lead screw 13 from the left (Fig. 1) to the right.

By placing handle 38 into the position A or C for grinding left hand threads oil under pressure passes through conduit 464 into cylinder 462 and shifts piston 46, the fork 475 and the sleeve 47 to the left, Figs. 29, 31. The lead screw 13 is driven by the gears 471, 474 and during the grinding of the threads the table 2 is moved from the right to the left by the lead screw 13. The direction of rotation of the work spindle 11 and of the lead screw 13 is reversed simultaneously by the said dogs 24 on the table 2 or by the shaft 30, spindle 33 and the discs 28, 29 after certain number of revolutions of the work spindle 11, the said numbers being determined by the size of angle α (Fig. 20).

While the direction of the movement of the table 2 is reversed after it has performed a travel of certain length determined by the distance at which the dogs 24 are apart or after the work spindle 11 and therewith the work piece has performed a certain number of revolutions the grinding disc S is moved in radial direction to and from the work piece.

The grinding disc S (Figs. 2, 3, 26) is fixed to a shaft 6 journalled in the slide 3 on which a motor and a change speed gear 7 is arranged. On the slide 3 a screw threaded sleeve 17 is fastened with which a spindle 16 is in engagement. On the spindle 16 a spur wheel 15 is fastened meshing with a spur wheel 215 (Fig. 2) the latter being keyed to a shaft 214 of a hand wheel 14 (Figs. 1, 3). By the hand wheel 14 the disc S may be adjusted manually. Moreover, hydraulic means are provided to actuate the slide 3 automatically and to feed the disc S in a predetermined manner with reference to the work piece. The spindle 16 is provided with a piston 51 (Figs. 12, 13, 14, 27) arranged in a cylinder 52 of the base 1. Pressure oil is fed to the cylinder 52 from the cylinder 36 if the piston 22 is at its right hand end position by a conduit 54, a valve 545 and the conduits 541, 143 and 144 (Fig. 12). The slide 3 is displaced until it abuts against a stud 56 fastened to a double armed lever 55 (Figs. 1, 2, 3, 4, 27). The slide 3 is moved towards the work against the action of a spring 240 (Fig. 12). One end of the spring 240 rests on a disc 241 on the base 1 the other end abuts on a ball bearing 242 held by nuts 243 of the spindle 16. With the piston 22 in its return stroke position in which case no pressure is in cylinder 52, the spring 240 tends to shift the slide 3 and the grinding disc S away from the work piece. To prevent jerks by reversing the travel of the slide 3 a fluid braking device (Figs. 12, 13, 14) is provided. The

spindle 16 has a bore 245, 246 (Fig. 13) in which a pin 57 is slidably mounted. The pin 57 has a conical end piece and carries a head 248. A coiled spring 141 arranged in the bore 246 tends to press the pin outwardly. Between the shoulder 2481 and the face 2482 remains a distance m (Figs. 12, 13). A stud 1421 fixed to the spindle 16 and engaging a groove 571 of pin 57 acts as a stop for said pin 57. When the slide 3 is in its backward position, and if the face 511 of the piston 51 rests on the face 140 there is between the stud 56 of lever 55 and the head 248 a distance equal to n . The gap Q between the orifice of bore 143 and the conical end piece of pin 57 is comparatively great.

By feeding the slide 3 hydraulically the carriage moves rapidly as the oil can flow into the cylinder 52 by the conduits 143 and 144 without any hindrance. As soon as the head 248 strikes against the stud 56 of lever 55 the pin 57 remains stationary while the piston 51 moves further until the face 2482 of the spindle 16 strikes against the face 2481 of the head 248. The carriage 3 has attained its foremost position. The speed at which the infeed of the slide takes place is continually reduced, while the piston 51 moves, the conical end piece of the pin 57 passes the channel 144 and enters the bore 143. The orifice of the bore 143 is partly closed, the cross-section Q (Fig. 12) through which the oil flows grows less and less to Q_1 (Fig. 14). In a like measure the speed of the slide 3 is reduced. The return movement of the slide 3 starts quickly. The oil in cylinder 52 flows-off through the conduits 143, 144, the ports in annular grooves 145, 146, conduit 541, valve 545 and pipe 544. When piston 51 has reached its rearmost position the edge 1451 (Fig. 13) of the annular groove 145 in the spindle 16 overlaps the edge 1461 of the annular groove 146 formed in the sleeve 244. The oil remaining in the cylinder 52 and in the ducts 143, 144 escapes through a small slot 147. The speed of the carriage is thereby greatly reduced shortly before it reaches its rearmost position.

The two armed lever 55 is rockingly mounted on a shaft 123 which is journalled in bearings 135, 136 of a support 250 (Figs. 1, 2, 3, 23). That portion of shaft 123 on which the lever 55 turns is eccentric with reference to the axis of the journals 135, 136 by an amount equal to X , Fig. 2. One arm 551 of lever 55 carries the stud 56 and in the other arm 552 a follower 58 is adjustably mounted. The latter contacts an arm 592 of a lever 59 (Figs. 3, 4, 23, 27). The lever 59 is rockingly mounted in the support 250 by two trunnions 591 (Figs. 4, 17). In the arm 593 a feeler 61 is continuously urged during the grinding operation into engagement with one cam of the set of cam discs 62, while a spring 260 (Figs. 4, 27) arranged between the support 250 and arm 593 tends to draw the feeler 61 away from the said set of cam discs 62. The action of the spring 260 is overcome by a piston 249 which urges the feeler 61 into contact with one cam of the cams 621 to 625 of the set of cam discs 62. The cam discs 621 to 625 are arranged side by side (Figs. 1, 2, 26).

The cam discs 621 to 625 are each of different throw (Fig. 18), and they are mounted by means of a key 632 on the sleeve 73 which latter is slidably mounted on a key of a shaft 63. Any one of the cams of the set of cam discs 62 may be brought opposite the feeler 61 by displacing the sleeve 73 on shaft 63. The movement of the pin 57 and therewith the movement of slide 3 may be varied by bringing any one of the discs

621 to 625 in co-operative position with feeler 61. By adjusting the follower 58 along a scale 76 (Figs. 2, 26) the distance R (Fig. 4) and therefore with the ratio transmission may be varied.

The shaft 63 is positively driven by shaft 9, toothed gears 300, 641 (Fig. 1), universal joint 642, shaft 64, universal joint 643 (Fig. 2), shaft 2611, gears 65 and change speed gears 66 interconnecting the shafts 2611, 2621 and 63. Figs. 21 and 22 illustrate the operation of the controlling device 57 to 63 for the infeed of slide 3. To cut screw threads in a work piece 71 (Fig. 21) ending very near the shoulder 711, the grinding disc S is axially displaced for a way equal to the way denoted by 12. The whole depth T of the threads is cut in a cycle of three consecutive operations or full strokes of the disc S. The three cuts T₁, T₂, T₃ are of different depth, the infeed of disc S is such that the work to be done by the disc S to cut a convolution of the thread is about the same for all the three working strokes of the work piece 71 and that the cross sections F₁, F₂, F₃ of the cuts are very near the same area. Owing to the short distance T₂ available for the axial displacement of the disc S each operation, that is a working stroke and a return stroke, is to be performed while the work piece 71 makes 1 1/4 revolutions denoted by 1 1/4U, Fig. 21. After the first working stroke the disc S has to be withdrawn from the work piece 71 and to be brought back to its new working position while the work piece 71 makes three quarters of a turn denoted in Fig. 21 by 3/4U. The infeed of disc S equal to T₁, or T₂, or T₃ and up to the points A₁, A₂, A₃ therefore is performed while the work piece 71 makes 3/4 of a full revolution at the start of a new working stroke. The disc S cuts down to the points P₁, P₂, P₃ at the three operations and remains working on the piece 71 while the same makes a full turn denoted by U, Fig. 21. The grinding disc S enters the work piece 71 while the latter is rotating. The disc S is quickly moved up to the point A₁ or A₂ or A₃ and then to the points P₁ or P₂ or P₃ at a lower speed. Change speed gears 65, 66 have to be inserted in the transmission train which turn the shaft 63 and the cam discs 62 for an angle $\beta + \gamma$ (Fig. 18) while the spindle 11 makes 1 1/4 turns. The angle β corresponds in the example to 3/4 and angle γ to a full revolution of the work piece 71. For each of the three operative strokes of the disc S and of slide 3 one different cam disc 621, 622, 623 is brought in position to work on the feeler 61. If a thread is to be cut in five operative strokes of disc S all the cam discs 621 to 625 are brought in action one by one and if a thread is to be finished in one stroke only one of the cams 62 is used. The cam is responsible for the displacement of the disc S from the point A₁ to the point P₁. It is only necessary to displace the follower 58 on the scale 76 of lever 55 (Fig. 4) to change the radius R and therewith the ratio of transmission of the throw H to the sliding pin 57 to cut threads of different depth.

The axial displacement of the sleeve 73 to bring any of the cam discs 621 to 625 opposite feeler 61 is effected while the disc S performs its return stroke and while the feeler 61 has been withdrawn from the work piece 71 by the spring 260. An angular lever 75 engaging with one arm an annular groove in the sleeve 73 is connected with its other arm and by a rod 74 (Figs. 1, 2, 21) to an arm 87 of a controller device 100 arranged at 18, Fig. 1. The arm 87 is fastened to shaft 86 (Figs. 1, 2, 9, 10, 11) rotatably mounted in the 76 wardly and rocks the angle lever 75. The sleeve

valve body 18. With the shaft 86 cooperates a rotary valve 100 which may be turned by a handle 95 (Figs. 1, 9, 10, 11, 15, 16).

The lever 95 may be placed in three positions E, F and G (Fig. 1) to control the infeed of the slide 3 by bringing one of the cam discs 621—625 into operative position or out of it.

(1) With the lever 95 in the position E (Fig. 1) the slide 3 is automatically moved to and fro the work piece and the set of cam discs 621—625 is automatically advanced on shaft 63.

(2) With the lever 95 in the position F the transverse feed of the slide 3 is performed by hand.

(3) With the lever 95 in the position G the shaft 9 and therewith spindle 11 and table 2 are automatically stopped and their movements are reversed at the end of a working stroke. The slide 3 may be advanced by hand (wheel 14, spindle 16).

With the lever 95 in the position E (Fig. 1) the sleeve 73 with the cam discs 621 to 625 is automatically shifted step by step during the return stroke of table 2 and while the grinding disc S has been taken off the work piece and while the feeler 61 has been taken off the cam discs 621 to 625 by means of the following device:

The piston 22 (Figs. 10, 11) is fixedly attached to a rod 221 having a reduced end portion on which a rack 81 is slidably mounted playing between the faces 226, 227. The rack 81 has a projection 81' with a slot through which extends a pin 225 screwed into the body 18. The head 225' of this pin 225 limits the axial displacement of the rack 81 to an amount equal to 0 (Fig. 11). The rack 81 partakes of the movement of piston 22 only if the latter has been displaced by a distance equal to p (Fig. 11) when being shifted to the right. The lapse of time between the start of the piston 22 and that of the rack 81 is sufficient to get the grinding disc S clear off the work piece and the feeler 61 from the cam discs 621 to 625 before the sleeve 73 is displaced.

The piston 22 moving to the left (Figs. 10, 11) does not take the rack 81 with it until the same is engaged by the face 227. The rack 81 turns the toothed gear 82 which is rigidly fixed to an arm 83 (Fig. 9). In a cylinder 102 of this arm 83 a fluid operated pawl 84 is arranged, adapted to be brought in engagement with a ratchet wheel 85 arranged at the side of arm 83 and rigidly connected to shaft 86. With the ratchet wheel 85 a second fluid operated pawl 88 is in engagement, which pawl 88 is arranged in a cylinder 103 of the body 18. The cylinder 103 communicates with the valve body 100 (Figs. 9, 27), by a duct 113 and bores in the shaft 86. The cylinder 102 communicates with the valve body 100 by a duct 112 in the arm 83, a longitudinal bore in shaft 86 and a transverse bore 101 in body 18. If lever 95 is in the position E for the automatic feeding of slide 3 no pressure prevails in the cylinders 102, 103 and the springs 841 and 881 keep the pawls 84 and 88 in engagement with the ratchet wheel 85. The teeth of the ratchet wheel 85 are formed in such a way that the same prevent a rotation of the wheel in anti-clockwise direction when the pawls 84 and 88 are engaged with the same.

The piston 22 moving to the left (Fig. 10) rotates the gear 82 by the rack 81 and therewith the arm 83 in clockwise direction. The pawl 84 turns the ratchet wheel 85 and therewith shaft 86 and the arm 87. The rod 74 is pushed down-wardly and rocks the angle lever 75. The sleeve

73 is moved to the right (Figs. 1, 2). The distance 0 which the rack 81 is moved is of such a length that the sleeve 73 is axially displaced the thickness of one cam of the set of cams disc 621 to 625.

The piston 22 moving to the right (Figs. 10, 11) shifts the rack 81 and turns therewith the gear 82 in anti-clockwise direction. The arm 83 is returned to its initial position. The ratchet wheel 85 the shaft 86 and all the parts rigidly connected therewith retain their position, the pawl 88 preventing a rotation of ratchet wheel 85. The pawl 84 slides over the teeth of ratchet wheel 85, the spring 841 yields.

At the succeeding return stroke the various operations are repeated. The operation of this device while performing the last working stroke will be described hereinafter.

To operate the slide 3 by hand the lever 95 is brought into the position F (Fig. 1). The valve body 100 is brought in a position in which oil under pressure passes into the cylinders 102, 103 (Figs. 9, 11, 23). The pawls 84, 88 are withdrawn from the disc 85. Any movement of piston 22 has no effect on the gearing for displacing the sleeve 73.

To stop the machine, the lever 95 has to be brought into the position G (Fig. 1). The machine may be set to rest by hand if the transverse feeding of the grinding disc S is effected by hand or automatically, if the slide 3 is automatically operated.

By bringing lever 95 into the position G, oil under pressure passes into the cylinders 102, 103 and the pawls 84, 88 are brought out of engagement with the disc 85. A spring 261, (Fig. 1) fixed with one end on bracket 250 and with the other on lever 75, is tensioned by displacing the sleeve 73 to the right. As soon as the pawls 84, 88 release the disc 85 the spring 261 retracts and draws the sleeve 73 to its initial position in which sleeve 73 rests on the shoulder 631 (Fig. 2) of shaft 63. The angle lever 75 moves thereby rod 74 upwardly, the arm 87 turns the shaft 86 and the disc 85 to their initial position. The feeler 61 is now opposite the first cam disc 621; at the same time the shaft 9 is stopped as follows: A pawl 91 arranged in a cylinder 97 of the valve body 18 stands under the action of a spring 92 which tends to insert the pawl 91 into a notch 93 of the piston rod 222. The cylinder 97 communicates by a pipe 96 with the valve body 100. By placing lever 95 into the position E and F (Fig. 1) oil under pressure passes into the cylinder 97 and brings the pawl 91 out of the notch 93. The piston 22 is free to move.

By placing lever 95 into position G, the cylinder 97 is emptied, the oil flows off by the conduit 96 and the valve body 100. The spring 92 expands and the pawl 91 stops the piston 22 as soon as it reaches its middle position (Fig. 10). In this position of piston 22 the lever 224 is in its upper position (Fig. 1) keeping the sleeve 19 out of contact with the wheels 20, 21. The shaft 9 is set to rest, the table 2, the spindle 11 and the lead screw are now in their initial position.

By grinding with automatic transverse feeding of the slide 3 the operations of the parts for stopping the machine proceed as follows:

The shaft 86 is turned at each stroke of the piston 22 to the left (Fig. 10). The machine is stopped after the piston 22 has reached its left hand end position. While the piston 22 is in the said position the lever 95 is brought into the position G. On the shaft 86 a disc 104 (Figs. 9, 16)

is arranged carrying a pin 105 projecting into one of a plurality of bores 107 in the head 108 of a sleeve 106 in which the shaft 86 is journaled. The disc 104 is loosely keyed to the outer reduced end of the shaft 86 and therefore rotates with the shaft 86 (Fig. 9). A knob 114 (Figs. 1, 9, 16) screwed on shaft 86 secures the disc 104 in its position. The head 108 of sleeve 106 has the numerals 0, 1, 2 and 3 applied thereto and on the disc 104 an index 115 is marked opposite said numerals. At the inner end of sleeve 106 a lever 98 is fastened co-operating with a disc 99 (Figs. 9, 15, 16) fixed to the valve body 100, the latter being operated by the lever 95. The lever 98 may be set with reference to the shaft 86 by means of placing pin 105 in any of the bores 107 in such a manner that the nose 981 of lever 98 comes to bear on the disc 99 fixed on pin 1001 of valve body 100 at the last part of the rotative movement of the shaft 86, bringing thereby the valve body 100 and lever 95 into position G to stop the machine.

To perform a full working cycle the piston 22 executes a certain number of working strokes. 25 On each stroke the piston 22 rocks the gear 82 and therewith arm 83. The pawl 84 turns the disc 85 and therewith shaft 86. The disc 104 being connected by pin 105 to sleeve 106 turns the latter and therewith the arm 98 step by step. 30 After, say for instance three steps, the nose 981 strikes against the disc 99 rigidly connected by the valve body 100 to the lever 95 and brings the latter to the position G, the "stop" position. The index 115 (Fig. 16) shows how many steps are 35 wanted to perform the full cycle of operations, it stands opposite the number 3. If four part working operations are to be executed, the pin 105 is displaced in another bore 107.

To start the machine again the lever 95 has 40 to be placed in either the position E or F (Fig. 1), according to the kind of work which has to be done. By displacing the lever 95 into said position oil under pressure enters the cylinder 97 and withdraws the stop 91 from the notch 93. 45 The piston 22 is free to move and brings the sleeve 19 in mesh with wheel 20 or wheel 21.

This device for shifting the sleeve 73 step by step can be used when grinding threads on cylindrical work pieces without flutes. To grind taps, 50 milling cutters and the like, an auxiliary device will be necessary to relieve the cutting edges of said tools.

This operation may be performed as illustrated in Fig. 22. A tap 120 with four flutes is 55 to be ground in a total working cycle of four full turns of said tap. The total depth T_{10} is reached by four consecutive operations. On the first revolution the disc S advances to T_{11} , in the second revolution to T_{12} in the third to T_{13} and in the finishing operation to T_{14} . The cross sections $F_{11}, F_{12}, F_{13}, F_{14}$ or the area cut at the four operations is of about the same size. The infeeding of the disc S from T_{11} to T_{12} etc. is effected 60 while the disc S passes over a flute of the tap. 65 In starting the disc S is brought into the position T_{11} . While the tap 120 makes one full turn the disc S performs the relieving movement four times. The disc S is fed to position T_{12} and while the tap makes the second revolution the disc S is again advanced and withdrawn four times from the tap to back-off of the cutting edges and so on. After the tap has made the four revolutions the slide 3 is fully withdrawn and this movement is initiated by the piston rod 22. 70 75 To control the movements of the slide 3 etc. the

set of cam discs 621 to 625 is replaced by one cam disc 629 (Fig. 7). The sleeve 73 is not shifted as described above. The shape of the cam disc 629 determines the relief which will be produced and the amount of it is indicated on a scale 76. Change speed gears 66 are brought in operation giving to cam 629 four full turns while the tap 120 makes but one full revolution. The shaft 63 makes four turns while spindle 11 makes but one full turn. To feed the disc S in the manner said, the lever 55 is mounted as described above on an eccentric 123. The eccentricity is denoted by X (Figs. 2, 26). If the shaft 123 is partly turned the bearing of lever 55 and therefore the axis of rotation thereof is displaced. The displacement of the axis of rotation of lever 55, that is the turning of shaft 123, is effected by a controlling disc 124 (Figs. 5, 6, 19, 23 to 25). The disc 124 is fast on a shaft 129 (Figs. 5, 6 and 26) journaled in the bracket 250 (Fig. 1). The shaft 129 is driven by the gearing 300, 641, 643, 642, 64, 2611 and the worm 125 and worm wheel 126. The latter is coupled to shaft 122 by a hand operated clutch member 139. The shaft 122 drives by the gears 127, 128 (Fig. 5) the shaft 129 and therewith the disc 124. An arm 133 (Figs. 5, 6) of a shaft 132 contacts with the disc 124 by a tooth 134. A second arm 131 of shaft 132 rests on a follower 137 adjustably mounted in a slot 138 of a lever 130 (Figs. 3, 6, 27) which is fast on the shaft 123. The lever 130 is provided with an arm 1301 (Figs. 3, 27) resting on a piston 263 arranged in a cylinder communicating by conduit 542 and 533 with cylinder 36 of piston 22. A spring 262 (Fig. 27) keeps arm 1301 in contact with piston 263. On the return stroke the disc 124 is returned too, it being positively driven by the shaft 9 and the gearing named above. The oil in conduit 542 flows off. The spring 262 withdraws the arm 133 from disc 124.

To make sure that the members 133 and 61 leave their respective cam discs 124 and 62 at the beginning of the return stroke of slide 3, that is as soon as the piston moves to the left (Fig. 10), the valve 545 (Fig. 27) is provided. The piston 22 is moved to the left by oil under pressure entering by the duct 34. At the same time oil is passed through conduit 342 into cylinder 546 (Fig. 27), the piston 545 is forced to the right (Fig. 27). Oil flows off from cylinder 52, and conduits 54, 541, 542, 543, 544 into a collecting chamber. The withdrawal of the members 3, 61 and 134 starts prior to the start of the return movement of the table 2 and the sleeve 73 with the cam disc 62. If oil under pressure passes by conduit 35 into cylinder 36 (Fig. 10), the oil from the conduits 34, 342 and 2311 flows off. A spring 547 (Fig. 27) shifts the piston 545 to the left until it rests on the face 548. In this position of piston 545 the conduits 54, 541 communicate and the slide 3 is fed towards the work piece as soon as oil under pressure passes from cylinder 36 through conduit 54.

In the circumference of disc 124 steps 124a, 124b, 124c, 124d etc. are formed over which the feeler 134 passes. The disc 124 rotates at such a speed that at each full turn of the work piece the disc 124 makes a part rotation equal to one field 124a (Fig. 19) that is equal to an angle of 34 degrees. After the work piece has made a full turn the disc 124 makes part of a rotation until the feeler 134 of lever 133 is brought to bear on the adjacent field 124b etc. By displacing the feeler 134 from one field 114a to 114b and so on for a

distance h_2 , h_3 etc. the position of the eccentric of the shaft 123 is altered for a corresponding amount. The lever 55 turns on the shaft 123 according to the throw of the cam discs 621 to 625 and controls the spindle 16 and the slide 3. The adjustment of the shaft 123 by the steps of disc 124 gives only that adjustment of the infeed of the tool S to attain the proper depth of the teeth of the tap. The steps h_2 to h_3 may be of different size and correspond to the different infeeds T_{10} to T_{14} of the grinding disc S (Fig. 22).

The infeed of the grinding disc S when the disc 124 is operative may be tabulated. If a convolution of a predetermined depth has to be ground certain steps 124a, 124b have to come in action to attain the desired depth, moreover the corresponding number of revolutions have to be ascertained.

A thread may be ground for instance in three full turns of the tap 120 making use of the three steps h_2 , h_3 , h_4 of the disc 124, or a thread may be formed in but two full revolutions of the tap by employing the steps h_4 and h_5 of disc 124.

In most cases the depth T_{10} of the thread to be formed in a work piece will not agree with the sum of any combination of steps h . Special means have to be provided to make possible the necessary correction. To explain the aforesaid description more fully an example is given:

30 A tap with a pitch of 2.5 millimeters and with a total depth of the thread $T_{10} = T_{11} + T_{12} + T_{13} + T_{14}$ equal to 1.749 millimeters is to be ground by disc S while the tap makes four full revolutions. The steps 124b, 124c, 124d, 124e of disc 124 are made use of to feed the disc S towards the tap. The feed of disc S by said steps would be say two millimeters that is too much. Only

$$\frac{1.749}{2 \times 100} = 87.45\%$$

40 of the whole distance has to be used. A correction in the rate of transmission is necessary and this correction may be obtained by adjusting the position of the pin 137. The divisions on scale 138 denote the percents of the whole way which are transmitted from the steps on disc 124 on to the disc S. In starting the grinding, the disc 124 is brought in such a position that the pin 134 of lever 133 contacts with the beginning of step 124b (Fig. 19). While the tap makes four full revolutions the disc S makes but three movements towards the tap and these correspond with the steps h_3 , h_4 and h_5 . The first feeding movement is given to disc S by the hand wheel 14 and is smaller than the way that would correspond to the depth h_2 , viz. it is only a part thereof. In the example given the feed movement of disc S is equal to 87.45% of the step h_2 . If the step h_2 measures for instance 0.7 millimeter only, a feeding way equal to 0.612 millimeter has to be given to disc S by the hand wheel 14. By the means described it will be possible to attribute to each revolution of the tap the same amount of grinding work to be effected by the disc S.

65 As seen from the above described example, the positions and the movements of the members essential to the function of the machine may be ascertained by calculation. The members, for instance pin 137, determining the feed of the disc S, may be set in advance into their proper position before starting the cutting of the screw threads.

The construction of the controlling device may be simplified if the first infeed movement of the disc S, that is the advance of the disc S to the

point T_{11} by means of the hand wheel 14 , is not made exactly in such a measure that the cross-sectional area F_1 of the cut at the first revolution of the tap is equal to the cross-sections F_2 and F_3 cut at the second and third etc. revolution of the tap.

The members 131 , 132 , and 133 are done away with. On the lever 130 (Figs. 23, 24, 25) the adjustable pin 137 is replaced by a pin 1371 rigidly connected to the lever 130 . The pin 1371 co-operates with the disc 124 mounted on the shaft 129 . The ratio of the transmission of the controlling movement from the disc 124 to the carriage 3 and disc S remains constant.

This modification of the device affects the working of the machine as will be apparent by the following calculation:

To cut in a tap a screw thread of 2.5 millimeter pitch and a total depth of the threads of 1.749 millimeters while the tap makes four full revolutions the same steps $124b$ to $124a$ as in the first example are made use of. The total sum of the steps $h_s = h_2 + h_3 + h_4 + h_5$ is again taken as equal to two millimeters. The first step h_2 of the disc 124 is equal to 0.7 millimeter. The disc S is advanced towards the work piece for 0.612 millimeter. At the first full revolution a cut with the cross-sectional area F_1 is made. If from the value $h_s = 2$ millimeters the value h_2 equal to 0.7 millimeter is deducted it remains a rest of $2 - 0.7 = 1.3$ millimeters. This advance of disc S is to be effected while disc 124 is advanced by a second, third and fourth step. If the advance of disc S produced by the steps on disc 124 is deducted from the total depth of the thread then remains the advance of the disc S to be given by the hand wheel 14 as equal to 0.449 that is $1.749 - 1.3 = 0.449$ millimeter.

It will be seen that the sectional area F_1 of the first cut may be slightly less or greater than that of the areas F_2 , F_3 etc. The difference is practically of no importance.

Screw threads may be cut on cylindrical work pieces in the straight or longitudinal grinding process in the following manner:

The table 2 is reciprocated and controlled by means of the dogs 24 . The slide 3 with disc S is adjusted by means of the hand wheel 14 or automatically, according to the positions of lever 95 . By grinding with automatic infeed of the slide 3 the set of cam discs 621 to 625 is made use of.

The disc 124 is only to be brought in operative position if the disc S has to be moved towards the work piece for instance when relief to the cutting edges of the teeth of a tap etc. has to be produced.

By grinding a work piece with the aid of the cam discs 621 to 625 the disc 124 has to be brought out of action. To bring the disc 124 in a position of rest, the worm wheel 126 is loosely mounted on the shaft 134 and may be coupled therewith by a clutch 139 (Fig. 5). To bring the disc 124 to its inactive position, the clutch 139 is brought out of engagement with the worm wheel 126 .

The dressing or profiling of the disc S may be effected with the machine by making use of some of the controlling devices. The profiling of disc S is performed by a roller 161 which is pressed on the disc S by hydraulic pressure which may be adjusted as required according to the hardness of the material of the disc S to be profiled; to the depth of the ribs to be formed and to the number thereof. The proper pressure for a particular disc S is to be found by experiments. The pressure of the fluid may be controlled by a pressure reducing valve or the like. By choosing the

best pressure much may be gained to reduce the wear of the roller, the time for the profiling of disc S may be greatly reduced too and the shape of the ribs produced on the ribs of disc S may be improved.

The valve mechanism 18 (Fig. 1) comprises a lever 151 co-operating with a valve 152 (Fig. 27) to adjust the pressure of the fluid for actuating the pressing roller 161 (Figs. 32, 34). With the lever in the position K (Fig. 1) the pressure fluid passes from a conduit 48 , pressure regulating valve 152 , duct 154 to an auxiliary valve 155 and over conduit 180 to a cylinder 169 (Fig. 33) in which a piston 156 is arranged. The piston 156 is connected by a link 157 to a double armed lever 158 rotatably mounted on a shaft 159 . On this shaft 159 an arm 160 is fastened in which the profiling roller 161 is rotatably mounted. The position of the lever 158 and of the arm 160 may be adjusted by an internally screw threaded sleeve 162 (Fig. 7). The latter is mounted on a hollow spindle 163 slidably on a key of shaft 161 . By means of a hand wheel 164 fixed on a shaft 165 and a set of bevel gears 166 the shaft 167 may be turned and the sleeve 163 advanced against the action of a spring 168 . The position of the sleeve 162 corresponds to the position of the roller 161 and the sleeve 162 is brought to a position in which the lever 158 may press on to sleeves 162 , 163 resting on spring 168 . The pressure of this spring 168 counteracts partly the fluid pressure exerted on piston 156 . If the fluid pressure in cylinder 169 falls inadvertently and when the profiling operation is finished, the expanding spring 168 withdraws the roller 161 from the disc S . A device to measure the reduction of the diameter of the disc S is combined with the sleeve 162 . On an arm thereof (Fig. 33) rests a follower 171 which transmits the movements of sleeve 162 on to an index playing over a scale of a measuring device 170 . The readings on this scale allow the proper re-adjustment of the slide 3 by the hand wheel 14 after a profiling of the disc S has taken place. From the pipe 154 a pipe 174 is branched off leading to pressure gauge 173 (Fig. 33).

To perform the profiling operation of disc S its speed is reduced by means of the change speed gear indicated at 7 in Fig. 33 and operated by a hand lever 174 (Figs. 1, 32, 33). By actuating lever 174 the latter presses on a piston 175 of valve 155 and displaces same against the action of a spring 176 . The piston 175 opens the way to the pressure fluid to the profiling device only by simultaneously setting the gearing 7 to drive the disc S at a reduced speed. The profiling operation by rollers is well known per se, moreover change speed gearings operated by a lever.

While the grinding disc S is working, the lever 151 is in the position T (Fig. 1). The communication of the main pressure conduit 48 with the duct 154 is broken. The latter is emptied over valve 152 and flow-off pipe 171 . With lever 174 in a position for rolling in the ribs, the cylinder 169 is emptied by the flow-off pipe 171 . By placing the lever 174 by inadvertence in that position which allows the high speed of the grinding disc S , the cylinder 169 is emptied over conduit 180 . It is impossible to start the rolling-in operation as long as grinding disc S is driven at high speed.

In the Figs. 27 to 31 the position of the different control members for the different operations are shown diagrammatically.

Fig. 27 illustrates the different mechanisms and the relative positions of the control elements

when producing by the so called longitudinal grinding process right handed screw threads in a work piece having no flutes, the transverse feed of the grinding disc S being exerted automatically.

The lever 38 of the valve mechanism is in the position B. The main piston valve 23 abuts on the face 3811 of the sleeve 381. The pilot valve 233 is in its left hand end position. The table 2 is moving to the right. The reversing is initiated by the dogs 24 striking against an arm of lever 25. The main piston 22 is in its right hand end position. The sleeve 19 is in engagement with gear 21. The piston 46 is in its right hand end position, the gears 472 and 473 are in mesh, and the lead screw spindle 13 advances the table 2 from left to right.

The knob 44 is turned loose and the clutch members 42, 43 set apart. In the cylinder 322 prevails no pressure, the parts 32 and 37 are disconnected, the shaft 33 is out of gear with shaft 9. The lever 95 is in its position E. The set of the cam disc 621 to 625 is automatically operated the machine is stopped after having performed five working strokes that is one full working cycle. The pawl 91 is out of the notch 93, the piston 22 is free to move. The pawls 84 and 88 are in engagement with the disc 85. The coupling 139 is open the shaft 122 is disconnected from shaft 611 and the disc 124 is at rest and performs no function. The shaft 63 is at a stand still, the change speed gears 66 have been removed. The set of cam discs 621 to 625 is displaced axially and the feeler 61 is brought in contact with any of them. The grinding disc S is advanced towards the work piece during the return stroke of slide 3. The slide 3 is in its operative position, the grinding disc S runs at high speed conforming to the position of the lever 174. The lever 151 is in the position T. The roller 161 is out of contact with the grinding disc S. The piston 175 of the valve 155 is in the uppermost position, the flow of oil through conduit 180 to conduit 154 is arrested. The oil passes off from cylinder 169 through slot 179 in piston 175. The piston of valve 545 is in left end position.

In Fig. 28 the various mechanisms of the machine are shown during the return stroke of table 2 and work spindle 11. The mechanism and the controlling device are in the position shown in Fig. 27 except as follows:

The piston of the pilot valve 233 is in its end position at the right and the main valve 23 is in its backward position touching face 181. The table 2 moves from the right to the left, the piston 22 is in its left hand end position. The sleeve 19 is in engagement with the gear 20. The feeler 61 has been moved away from the cam discs for instance from cam disk 623. The sleeve 73 is shifted by angle lever 75 to the right and for as much as a cam disc. The slide 3 is in its back position. Between the pin 57 and the stud remains a space equal to n . The grinding disc S is rotated at high speed during the return stroke. The piston of valve 545 has been moved to the left allowing the passage of oil to pipe 54.

Fig. 29 illustrates the position of the parts of the machine by producing left hand threads in work pieces having no flutes according to the longitudinal grinding process.

The grinding disc S is fed towards the work piece by hand wheel 14. The lever 38 is in the position A. The valve piston 23 touches the face 181. The piston of pilot valve 233 is at the right hand end. The table 2 travels from right to left.

The reversing is effected by the action of the dogs 24 on lever 25. The main piston 22 is at the right hand end position. The sleeve 19 is in engagement with the toothed gear 21 the gearing 5 is set for a working stroke. The piston 46 of valve 47 is in its left hand end position. The gear 474 is driven by gear 471 and the lead screw 13 drives the table from the right to the left, that is the direction necessary for grinding left hand threads. The knob 44 and the coupling of the parts 42, 43 is loose. No pressure prevails in cylinder 322 and the parts 32 and 37 are out of engagement. The shaft 33 is set to rest. The lever 95 is in the position F. The pawls 84, 88 are out of mesh with disc 85. The indexing device 104, 108 is not used as the machine is stopped by hand by the operator after any number of working strokes. The sleeve 73 is held in its position at the shoulder 631 by the spring 261.

The shaft 63 remains at rest, the change speed gears 66 have been removed. The feeler 61 rests on cam disc 621 and remains in this position while the working cycle is proceeding. The catch 91 is out of notch 93, the piston 22 is free to move. The coupling 139 is loose, the disc 124 has not to perform any work.

Fig. 30 shows the position of the controlling devices, while the rolling-in of the ribs on the grinding disc S takes place. The different steering mechanisms are shown in that position of the parts of the machine in which right hand threads are formed by the plunge grinding process and by giving relief to the teeth of a fluted tap or the like.

The lever 38 is in the position D. The piston 23 is in touch with face 3811 of cap 381, the piston of the pilot valve 233 is at its left end position. The machine and therefore table 2 is at rest. When starting the machine, the table 2 will move from the left to the right. During the working stroke the reversing of the travel of table 2 is effected by the discs 28, 29 on shaft 33, co-operating with the lever 27. The piston 22 is at its middle position, the sleeve 19 is out of engagement with the toothed gears 20, 21. The shaft 9 is at rest. The clutches 42, 43, 44 are closed. Oil under pressure enters the cylinder 322, the parts 32, 37 are coupled and the shaft 33 is rotated. The index 432 is set over the markings 50 421 to make the number of working strokes to correspond with the number of steps on the disc 124 chosen for carrying out the particular work. The face 291 of disc 29 is in contact with lever 272. The lever 95 is in the position C. The pawls 84 and 88 are out of mesh with disc 85. The catch 91 engages notch 93 and locks the piston 22.

During a complete working cycle only one reversal takes place. The clutch 139 is closed and the disc 124 is ready for action. While the machine is working the shaft 63 is rotated. The change speed gears 66 are calculated to turn the shaft 63 for a complete revolution while the tap turns for one flute to another. The sleeve 73 is not moved in axial direction, the spring 261 draws the sleeve 73 on to the shoulder 631. Only one disc 62 is used having a curvature designed for performing the relieving movement. With the machine at rest the feelers 61 and 1371 are withdrawn from their contacting position with the discs 629 and 124 respectively. The slide is in its back position. The grinding disc S rotates at reduced speed conforming to the position given to lever 174. The lever 151 is in the position K. The roller 161 is pressed on the grinding disc S.

The piston 175 of the valve 155 has been moved downwardly. Oil under pressure passes into cylinder 169 pressing the roller 161 on to the grinding disc S. Fig. 31 shows the relative positions of the controlling mechanism, etc., of the machine by producing left hand threads by the plunge grinding process on a work piece having no flutes. The infeed of the grinding disc S being performed automatically.

The lever 38 is in position C. The piston valve 23 is in touch with face 3811 of sleeve 381. The piston of pilot valve 233 is in its left hand end position, the table 2 moves from the right to the left during the working stroke. The reversing as initiated by the discs 28, 29 co-operating with lever 27. The piston 22 is in the right hand end position. The sleeve 19 is coupled with gear 21. The piston 46 is in its left hand end position. The gear 471 is in mesh with gear 474 and drives the lead screw 13 to advance the table 2 during the working stroke from the right to the left, as left handed threads are to be cut. The coupling of the parts 42, 43, 44 is closed. In cylinder 322 there is oil under pressure, the parts 32, 37 are in mesh. The shaft 33 is rotating. The index 432 is placed on the scale 421 in such a manner that after each single working stroke a return stroke is taking place. The lever 95 is placed in the position E. The five cam discs 621 to 625 are shifted one by one. The index 108 is placed on the scale 104 in such a position that the machine is automatically stopped after five single working strokes have been performed. The catch 91 has been brought out of notch 93, the piston 22 is free to move. The pawls 84, 88 are in engagement with the disc 85. The disc 124 is disconnected from the drive, the clutch 139 is open. The shaft 63 is rotating. The change speed gears 66 are calculated to let the shaft 63 to turn for one full revolution while the spindle 11 performs 2½ revolutions. On the sleeve 73 there are five cam discs 621 to 625, the sleeve 73 is fed step by step to place one of said cam discs opposite the feeler 61 at each single working stroke. The table 2 performs the first working stroke. The grinding disc S works in a convolution already formed. The feeler 61 is on the cylindrical portion of the first cam disc 621. The grinding disc S is not radially advanced towards the work piece. The sleeve 73 rests on the shoulder 631. The grinding disc S turns at high speed.

What I wish to secure by United States Letters Patent is:

1. In a screw thread grinding machine, a base, a table slidably mounted on said base, means for reciprocating said table along said base, means for rotatably supporting a workpiece, said means including a headstock mounted on said table, and a work spindle rotatably mounted in said headstock, and adapted to rotate the workpiece, means for driving said work spindle, a tool slide mounted on said base movable at a right angle to the path of movement of said table, a rotary grinding disk on a shaft and an independent power drive for said shaft mounted on said tool slide, said grinding disk having a plurality of annular grinding ribs for simultaneously producing a plurality of thread convolutions on the workpiece, manually operable means for moving said tool slide including a shaft rotatably mounted in said base and in threaded engagement with said tool slide, and fluid pressure operated means adapted to automatically move said tool slide to advance the grinding disk toward the workpiece on said table.

independently of said manually operable means, said fluid pressure operated means including a piston fixed on said last named shaft which is in threaded engagement with said tool slide, a cylinder for said piston formed by a cylindrical recess in said base, means for conducting fluid pressure into said cylinder for causing a displacement of said piston and therewith said last named shaft in axial direction, cam means operatively connected with said work spindle driving means and operated thereby in timed relation to said work spindle for controlling and limiting the axial movement of said piston in a direction in which the grinding disc moves toward the workpiece in a predetermined number of successive passes, and means for adjusting said cam means to the desired number of grinding passes and to the desired amount of feed for each grinding pass prior to the beginning of the grinding operation.

2. In a screw thread grinding machine, a base, a table slidably mounted on said base, means for reciprocating said table along said base, means for rotatably supporting a workpiece, said means including a headstock mounted on said table, and a work spindle rotatably mounted in said headstock, and adapted to rotate the workpiece, means for driving said work spindle a tool slide mounted on said base movable at a right angle to the path of movement of said table, a rotary grinding disk on a shaft and an independent power drive for said shaft mounted on said tool slide, said grinding disk having a plurality of annular grinding ribs for simultaneously producing a plurality of thread convolutions on the workpiece, manually operable means for moving said tool slide including a shaft rotatably mounted in said base and in threaded engagement with said tool slide, and fluid pressure operated means adapted to automatically move said tool slide to advance the grinding disk toward the workpiece on said table independently of said manually operable means, said fluid pressure operated means including a piston fixed on said last named shaft which is in threaded engagement with said tool slide, a cylinder for said piston formed by a cylindrical recess in said base, means for conducting fluid pressure into said cylinder for causing a displacement of said piston and therewith said last named shaft in axial direction, cam means operatively connected with said work spindle driving means and operated thereby in timed relation to said work spindle for controlling and limiting the axial movement of said piston in a direction in which the grinding disc moves toward the workpiece in a predetermined number of successive passes, and means for adjusting said cam means prior to the beginning of the grinding operation to the desired number of grinding passes and to such amounts of feed so that the grinding disc performs in all the said passes substantially the same amount of work.

3. In a screw thread grinding machine, a base, a table slidably mounted on said base, means for reciprocating said table along said base, means for rotatably supporting a workpiece, said means including a headstock mounted on said table, and a work spindle rotatably mounted in said headstock, and adapted to rotate the workpiece, means for driving said work spindle, a tool slide mounted on said base movable at a right angle to the path of movement of said table, a rotary grinding disk on a shaft and an independent power drive for said shaft mounted on said tool slide, said grinding disk having a plurality of annular grinding ribs for simultaneous-

ly producing a plurality of thread convolutions on the workpiece, manually operable means for moving said tool slide including a shaft rotatably mounted in said base and in threaded engagement with said tool slide, fluid pressure operated means adapted to automatically move said tool slide to advance the grinding disk toward the workpiece on said table independently of said manually operable means, means to reverse the travel of said tool slide, and means to automatically stop the machine, said fluid pressure operated means including a piston fixed on said last named shaft which is in threaded engagement with said tool slide, a cylinder for said piston, means for conducting fluid pressure into said cylinder for moving said piston and therewith said last named shaft in axial direction, cam means operatively connected with said work spindle driving means and operated thereby in timed relation to said work spindle for controlling and limiting the axial movement of said piston in a direction in which the grinding disc moves toward the workpiece in a predetermined number of successive passes, and means for adjusting said cam means to the desired number of grinding passes and to the desired amount of feed for each grinding pass prior to the beginning of the grinding operation.

4. In a screw thread grinding machine, a base, a table slidably mounted on said base, means for reciprocating said table along said base, means for rotatably supporting a workpiece, said means including a headstock mounted on said table, and a work spindle mounted in said headstock and adapted to rotate the workpiece, means for driving said work spindle, a tool slide mounted on said base movable at a right angle to the path of movement of said table, a rotary grinding disc on a shaft and an independent power drive for said shaft mounted on said tool slide, said grinding disc having a plurality of annular grinding ribs for simultaneously producing a plurality of thread convolutions on the workpiece, manually operable means for moving said tool slide including a shaft rotatably mounted in said base and in threaded engagement with said tool slide, and fluid pressure operated means adapted to automatically move said tool slide to advance the grinding disc toward the workpiece on said table independently of said manually operable means, said fluid pressure operated means including a piston fixed on said last named shaft which is in threaded engagement with said tool slide, a cylinder for said piston formed by a cylindrical recess in said base, means for conducting fluid pressure into said cylinder for causing a displacement of said piston and therewith said last named shaft in axial direction, means for controlling and limiting the axial movement of said piston in a direction in which the grinding disc moves toward the workpiece in a predetermined number of successive passes, said controlling means including a shaft, means drivingly connecting said last named shaft with said work spindle, whereby said last named shaft is driven by said work spindle, a plurality of cam discs mounted as a unit axially slidably on said last named shaft and rotated by the latter, one cam disc for each grinding pass, a lever pivotally supported between its ends and projecting with one of its ends into the path of movement of said piston to limit the axial feed movement of the same, a feeler engaging one of said cam discs, means for transmitting the movement of said feeler as caused by said rotating cam disc to the other end of said pivotally supported lever, and means for slidably adjusting said plurality of cam discs for bringing another cam disc in engagement with said feeler at the end of each of said grinding passes, the cam discs having such a shape that during each of the successive grinding passes the grinding disc performs substantially the same amount of work on the work piece.

other end of said pivotally supported lever, and means for slidably adjusting said plurality of cam discs for bringing another cam disc in engagement with said feeler at the end of each of said grinding passes.

5. In a screw thread grinding machine, a base, a table slidably mounted on said base, means for reciprocating said table along said base, means for rotatably supporting a workpiece, said means including a headstock mounted on said table, and a work spindle mounted in said headstock and adapted to rotate the workpiece, means for driving said work spindle, a tool slide mounted on said base movable at a right angle to the path of movement of said table, a rotary grinding disc on a shaft and an independent power drive for said shaft mounted on said tool slide, said grinding disc having a plurality of annular grinding ribs for simultaneously producing a plurality of thread convolutions on the workpiece, manually operable means for moving said tool slide including a shaft rotatably mounted in said base and in threaded engagement with said tool slide, and fluid pressure operated means adapted to automatically move said tool slide to advance the grinding disc toward the workpiece on said table independently of said manually operable means, said fluid pressure operated means including a piston fixed on said last named shaft which is in threaded engagement with said tool slide, a cylinder for said piston formed by a cylindrical recess in said base, means for conducting fluid pressure into said cylinder for causing a displacement of said piston and therewith said last named shaft in axial direction, means for controlling and limiting the axial movement of said piston in a direction in which the grinding disc moves toward the workpiece in a predetermined number of successive passes, said controlling means including a shaft, means drivingly connecting said last named shaft with said work spindle, whereby said last named shaft is driven by said work spindle, a plurality of cam discs mounted as a unit axially slidably on said last named shaft and rotated by the latter, one cam disc for each grinding pass, a lever pivotally supported between its ends and projecting with one of its ends into the path of movement of said piston to limit the axial feed movement of the same, a feeler engaging one of said cam discs, means for transmitting the movement of said feeler as caused by said rotating cam disc to the other end of said pivotally supported lever, and means for slidably adjusting said plurality of cam discs for bringing another cam disc in engagement with said feeler at the end of each of said grinding passes, the cam discs having such a shape that during each of the successive grinding passes the grinding disc performs substantially the same amount of work on the work piece.

6. In a screw thread grinding machine, a base, a table slidably mounted on said base, means for reciprocating said table along said base, means for rotatably supporting a workpiece, said means including a headstock mounted on said table, and a work spindle mounted in said headstock and adapted to rotate the workpiece, means for driving said work spindle, a tool slide mounted on said base movable at a right angle to the path of movement of said table, a rotary grinding disc on a shaft and an independent power drive for said shaft mounted on said tool slide, said grinding disc having a plurality of annular grinding ribs for simultaneously producing a plurality of thread convolutions on the workpiece, manually operable means for moving said tool slide including a shaft, means drivingly connecting said last named shaft with said work spindle, whereby said last named shaft is driven by said work spindle, a plurality of cam discs mounted as a unit axially slidably on said last named shaft and rotated by the latter, one cam disc for each grinding pass, a lever pivotally supported between its ends and projecting with one of its ends into the path of movement of said piston to limit the axial feed movement of the same, a feeler engaging one of said cam discs, means for transmitting the movement of said feeler as caused by said rotating cam disc to the other end of said pivotally supported lever, and means for slidably adjusting said plurality of cam discs for bringing another cam disc in engagement with said feeler at the end of each of said grinding passes, the cam discs having such a shape that during each of the successive grinding passes the grinding disc performs substantially the same amount of work on the work piece.

rality of thread convolutions on the workpiece, manually operable means for moving said tool slide including a shaft rotatably mounted in said base and in threaded engagement with said tool slide, and fluid pressure operated means adapted to automatically move said tool slide to advance the grinding disc toward the workpiece on said table independently of said manually operable means, said fluid pressure operated means including a piston fixed on said last named shaft which is in threaded engagement with said tool slide, a cylinder for said piston formed by a cylindrical recess in said base, means for conducting fluid pressure into said cylinder for causing a displacement of said piston and therewith said last named shaft in axial direction, means for controlling and limiting the axial movement of said piston in a direction in which the grinding disc moves toward the workpiece in a predetermined number of successive passes, said controlling means including a shaft, means drivingly connecting said last named shaft with said work spindle, whereby said last named shaft is driven by said work spindle, a plurality of cam discs mounted as a unit axially slidably on said last named shaft and rotated by the latter, one cam disc for each grinding pass, a lever pivotally supported between its ends and projecting with one of its ends into the path of movement of said piston to limit the axial feed movement of the same, a feeler engaging one of said cam discs, means for transmitting the movement of said feeler as caused by said rotating cam disc to the other end of said pivotally supported lever, hydraulically operated shifting means for automatically adjusting said plurality of cam discs along said last named shaft at the end of each working cycle of said table to bring the next cam disc in engagement with said feeler.

7. In a screw thread grinding machine, a base, a table slidably mounted on said base, means for reciprocating said table along said base, means for rotatably supporting a workpiece, said means including a headstock mounted on said table, and a work spindle mounted in said headstock and adapted to rotate the workpiece, means for driving said work spindle, a tool slide mounted on said base movable at a right angle to the path of movement of said table, a rotary grinding disc on a shaft and an independent power drive for said shaft mounted on said tool slide, said grinding disc having a plurality of annular grinding ribs for simultaneously producing a plurality of thread convolutions on the workpiece, manually operable means for moving said tool slide including a shaft rotatably mounted in said base and in threaded engagement with said tool slide, and fluid pressure operated means adapted to automatically move said tool slide to advance the grinding disc toward the workpiece on said table independently of said manually operable means, said fluid pressure operated means including a piston fixed on said last named shaft which is in threaded engagement with said tool slide, a cylinder for said piston formed by a cylindrical recess in said base, means for conducting fluid pressure into said cylinder for causing a displacement of said piston and therewith said last named shaft in axial direction, means for controlling and limiting the axial movement of said piston in a direction in which the grinding disc moves toward the workpiece in a predetermined number of successive passes, said last named means including a plurality of cam discs, one for each grinding pass, means for rotating said plurality of cam discs as a unit, and a pivotally mounted lever cooperating with any one of said cam discs and projecting with one of its ends into the path of movement of said piston to limit the axial movement of the same.

8. In a screw thread grinding machine, a base, a table slidably mounted on said base, means for reciprocating said table along said base, means for rotatably supporting a workpiece, said means including a headstock mounted on said table and a work spindle mounted in said headstock and adapted to rotate the workpiece, means for driving said work spindle, a tool slide mounted on said base movable at a right angle to the path of movement of said table, a rotary grinding disc on a shaft and an independent power drive for said shaft mounted on said tool slide, said grinding disc having a plurality of annular grinding ribs for simultaneously producing a plurality of thread convolutions on the workpiece, manually operable means for moving said tool slide including a shaft rotatably mounted in said base and in threaded engagement with said tool slide, and fluid pressure operated means adapted to automatically move said tool slide to advance the grinding disc toward the workpiece on said table independently of said manually operable means, said fluid pressure operated means including a piston fixed on said last named shaft which is in threaded engagement with said tool slide, a cylinder for said piston formed by a cylindrical recess in said base, means for conducting fluid pressure into said cylinder for causing a displacement of said piston and therewith said last named shaft in axial direction, means for controlling and limiting the axial movement of said piston in a direction in which the grinding disc moves toward the workpiece in a predetermined number of successive passes, said last named means including a plurality of cam discs, one for each grinding pass, means for rotating said plurality of cam discs as a unit, and a pivotally mounted lever cooperating with any one of said cam discs and projecting with one of its ends into the path of movement of said piston to limit the axial movement of the same, a feeler engaging one of said cam discs, means for transmitting the movement of said feeler as caused by said rotating cam disc to the other end of said pivotally supported lever, hydraulically operated shifting means for automatically adjusting said plurality of cam discs along said last named shaft at the end of each working cycle of said table to bring the next cam disc in engagement with said feeler, means operatively connecting said cam disc shifting means with a table movement reversing means, and manually operable means for manually adjusting said cam disc shifting means.

9. In a screw thread grinding machine, a base, a table slidably mounted on said base, means for reciprocating said table along said base, means for rotatably supporting a workpiece, said means including a headstock mounted on said table and a work spindle mounted in said headstock and adapted to rotate the workpiece, means for driving said work spindle, a tool slide mounted on said base movable at a right angle to the path of movement of said table, a rotary grinding disc on a shaft and an independent power drive for said shaft mounted on said tool slide, said grinding disc having a plurality of annular grinding ribs for simultaneously producing a plurality of thread convolutions on the workpiece, manually operable means for moving said tool slide including a shaft rotatably mounted in said base and in threaded engagement with said tool slide, and fluid pressure operated means adapted to automatically move said tool slide to advance the grinding disc toward the workpiece on said table independently of said manually operable means, said fluid pressure operated means including a piston fixed on said last named shaft which is in threaded engagement with said tool slide, a cylinder for said piston formed by a cylindrical recess in said base, means for conducting fluid pressure into said cylinder for causing a displacement of said piston and therewith said last named shaft in axial direction, means for controlling and limiting the axial movement of said piston in a direction in which the grinding disc moves toward the workpiece in a predetermined number of successive passes, said last named means including a plurality of cam discs, one for each grinding pass, means for rotating said plurality of cam discs as a unit, and a pivotally mounted lever cooperating with any one of said cam discs and projecting with one of its ends into the path of movement of said piston to limit the axial movement of the same.

10. In a screw thread grinding machine, a base, a table slidably mounted on said base, means for reciprocating said table along said base, means for rotatably supporting a workpiece, said means including a headstock mounted on said table and a work spindle mounted in said headstock and adapted to rotate the workpiece, means for driving said work spindle, a tool slide mounted on said base movable at a right angle to the path of movement of said table, a rotary grinding disc on a shaft and an independent power drive for said shaft mounted on said tool slide, said grinding disc having a plurality of annular grind-

ing ribs for simultaneously producing a plurality of thread convolutions on the workpiece, manually operable means for moving said tool slide including a shaft rotatably mounted in said base and in threaded engagement with said tool slide, and fluid pressure operated means adapted to automatically move said tool slide to advance the grinding disc toward the workpiece on said table independently of said manually operable means, said fluid pressure operated means including a piston fixed on said last named shaft which is in threaded engagement with said tool slide, a cylinder for said piston formed by a cylindrical recess in said base, means for conducting fluid pressure into said cylinder for causing a displacement of said piston and therewith said last named shaft in axial direction, and means adapting the machine for grinding taps, milling cutters and the like, said last named means including a rotating cam disc, a pivotally mounted lever cooperating with said cam disc and projecting with one of its ends into said path of movement of said piston to control and limit the said movement of said grinding disc toward a

5

fluted workpiece, and a controlling disc operable to shift the pivot axis of said lever during the rotation of said cam disc to modify thereby the feed movement of said grinding disc to such an extent that it radially relieves the cutting teeth formed on the fluted workpiece during each revolution of said workpiece.

ALFRED RICKENMANN.
